UNITED STATES PATENT OFFICE

FRANK E. RUDD, OF LOUISVILLE, KENTUCKY

DESIGN FOR A TEXTILE FABRIC

Application filed January 7, 1931. Serial No. 38,231. Term of patent 3½ years.

To all whom it may concern:

Be it known that I, FRANK E. RUDD, a citizen of the United States and a resident of Louisville, county of Jefferson, State of Kentucky, have invented a new, original, and ornamental Design for Textile Fabric, of which the following is a specification, reference being had to the accompanying drawing forming part hereof, in which is shown a plan view of a piece of textile fabric embodying my design. The unit of the design is simply repeated on all sides and corners in the same relative positioning.

I claim:—

The ornamental design for a textile fabric substantially as illustrated and described.

In testimony whereof, I have signed my name to this specification this 2d day of January, 1931.

FRANK E. RUDD.
